(57) **CLAIM**

The ornamental design for a tee prong and golf club handle fork, as shown and described.

DESCRIPTION

FIG. 1 is a top isometric view of a tee prong and golf club handle fork showing the tee shaped prongs and club like grip arrangement of my new fork design;

FIG. 2 is a top view thereof, the bottom view being a mirror image thereof;

FIG. 3 is a right side view thereof, the left side view being a mirror image thereof;

FIG. 4 is a bottom view thereof;

FIG. 5 is a front view thereof; and,

FIG. 6 is a back view thereof.
